EMERGENCY CONTROL APPARATUS FOR
CENTRALIZED TRAFFIC CONTROL SYS-
TEMSThomas W. Hays, Salt Lake City, Utah, assignor
to The Union Switch and Signal Company,
Swissvale, Pa., a corporation of Pennsylvania

Application June 5, 1947, Serial No. 752,602

11 Claims. (Cl. 246—3)

1

My invention relates to emergency control apparatus for centralized traffic control systems for the control of traffic movements over single track railroads, and more particularly to systems of this character employing cascade reversible track or line circuits which are arranged to be set up for traffic movements in either direction by manual control from a central office.

The principal object of my invention is the provision of means for maintaining such a signaling system in operation for either direction of traffic movement under emergency conditions, as for example, in the event of a fault which renders the communication system inoperative.

In my prior application for Letters Patent of the United States, Serial No. 553,689, filed September 12, 1944, now Patent No. 2,430,291, issued Nov. 4, 1947, I disclosed a system for the same general purpose which employs manual switching means at each signal location by which the reversible line circuit system which employs two line wires for signal control under centralized operation may be converted in an emergency to a four line wire automatic block system by using the two communication system line wires for the two additional line wires needed.

In accordance with the present invention no manual switching is necessary at the various signal locations to set up the system for either direction operation under emergency conditions, but the system is so arranged that it reverts automatically to a condition suitable for emergency operation as a result of a failure of the code line circuit, or the apparatus at any station may be placed in the emergency condition by remote control by means of the communication system enabling the latter to remain in service for the control of apparatus at other stations.

In single track signaling systems of the types to which my invention is particularly applicable, the reversible signaling system is normally arranged to be set up for either direction of traffic movement by the operation of two traffic relays, one at each end of the block, which relays are operable to corresponding positions designating the desired traffic direction by control codes transmitted from the central office. To clear an entering signal for a train movement through a block in a direction already established, it is necessary merely to transmit a code to the entering signal location to reverse the control relay for the signal. Under proper traffic conditions, that is, when the block is unoccupied and the entering signals are properly at stop, the entering signal for the direction opposing that for

2

which the signal circuits are set up may be cleared, the code transmitted to the signal location in this case acting to reverse both the traffic relay and the signal control relay at that location. The operation of this traffic relay de-energizes the reversible signal system to restore the opposing intermediate signals to stop and connects a signal relay for the adjacent entering signal thereto. In addition, a control code is transmitted automatically which operates the traffic relay at the opposite end of the block to a position to disconnect the signal relay and to supply energy at that end to the reversible signaling system so as to effect its energization in the desired direction.

The operation of systems of this character as hereto constituted presented the difficulty that under emergency conditions involving a failure of the communication system, there was no convenient way to operate the traffic relay at the remote end of the block as required for the emergency control of the signals for one direction.

This difficulty is overcome in accordance with the present invention by the provision of an emergency relay at each field station which may be selectively energized by temporarily opening the communication line circuit. This relay, when energized, transfers the control of the signal control and traffic relays from the remote control system to emergency levers or push buttons which may be manipulated by a local operator or by the crew of a train. The traffic relay which governs the direction of energization of the signal circuits for the adjoining single track stretch assumes its exit end position as required for clearing the entering signal at the opposite end of the stretch. Each traffic relay assumes its entrance end position as required for clearing the entering signal at the same location in response to the operation of the emergency lever or push button for that signal, reverting to its exit end position when such signal is accepted by a train.

The system of my invention thus provides "entrance and control" of traffic movements in either direction and thereby facilitates the movement of traffic through the blocks equipped with reversible signal circuits under emergency conditions.

I shall describe one form of apparatus embodying my invention and shall then point out the novel features thereof in claims.

Referring to the accompanying drawings, Fig. 1A shows the track plan and the circuits and apparatus at a typical field station located at the

left-hand end of a single track block, while Fig. 1B shows the similar but oppositely directed apparatus at the right-hand end of a single track block. Since consideration of the apparatus at intermediate signal locations is not needed for an understanding of my invention, these have been omitted and the reversible signal circuits are assumed to extend directly from Fig. 1A to Fig. 1B over the line wires 28 and 29. The drawings may also be arranged to show the circuits for the passing track area in their entirety by placing Fig. 1B at the left of Fig. 1A, the line wires 40-42 which extend to the right hand margin of Fig. 1B matching those similarly designated which extend to the left-hand margin of Fig. 1A.

Similar reference characters refer to similar parts in both views. To simplify the various circuits the local sources of current for energizing the various relays are identified by their terminals which are designated B and C, respectively.

The centralized traffic control system to which my invention is applied as shown herein is generally similar to that shown in my prior application hereinbefore referred to and corresponds to that disclosed in a United States patent application, Serial No. 501,254, filed September 4, 1943, by Henry S. Young for Railway Traffic Controlling Apparatus, now Patent No. 2,420,579, issued May 13, 1947, but to simplify the drawings the circuits have been modified in a number of respects to eliminate elements not needed for an understanding of my invention. The communication system by which the manual control of the switches and signals is effected is to be understood to be a modification of the one employed in connection with my prior application which corresponds to that shown in Letters Patent of the United States No. 2,411,375, issued November 19, 1946, to Arthur P. Jackel for Remote Control Systems.

The communication system comprises a plurality of coding units at the control office, not shown herein, and one at each field station as indicated by the legends "C. T. C. Station No. 1" in Fig. 1A and "C. T. C. Station No. 3" in Fig. 1B. The office and station coding units are connected by a normally energized circuit including the line wires Y and Z extending through each station in turn, over which indication codes are transmitted in response to changes in trackway conditions to indicate the condition of the station apparatus and to govern traffic direction controlling apparatus at the office as described in the Young application above referred to. A line relay 1R or 3R, at each station, is connected across the line wires Y and Z and is normally held energized by current from a battery 20 located at the office. Control codes are transmitted by interrupting the line circuit by the operation of a transmitter relay T at the office, and in response to these codes the line relays operate their respective coding units in such manner as to effect the operation of each of a group of polar stick control relays to normal or reverse at a selected station only, in accordance with the character of the elements of the code. As shown in Fig. 1A, the code controlled relays at Station No. 1 include a switch control relay 1WS operable to normal or reverse by impulses supplied over wires 9 and 11, which relay governs the switch machine 1SM for the track switch 1W, a traffic relay 2RFS controlled by impulses of normal or reverse polarity supplied over wires 10 and 82, a signal control relay 2LHS similarly

controlled over wires 13 and 81 for governing the clearing of signals 2LA and 2LB, and a signal control relay 2 RHS controlled over wires 15 and 81 for governing the clearing of the entering signals 2RA and 2RB for the single track block. The switch machine 1SM is of the dual control type, controlled by a selector lever having a "power" position in which the dual selector contacts DS are closed and the switch is coupled to a motor to render it operable by power in accordance with the position of relay 1WS, and also having a "hand" position in which the switch is operable by a hand throw lever, not shown, and in which the dual selector contacts DS are open. The switch 1W and its control relay 1WS jointly control a normal and a reverse switch indication relay 1NWP and 1RWP, contacts of which serve to select the "A" or "B" signal for clearing in accordance with the route established by switch 1W.

The C. T. C. Station No. 3 in Fig. 1B controls a similar group of relays which govern the operation of switch 3W and of signals 4LA, 4LB, 4RA and 4RB in a corresponding manner, this group including a traffic relay 4LFS which jointly with relay 2RFS governs the reversible line circuit system including the line wires 28 and 29.

As shown by the track plan, the main track is divided into sections 1T, 2RT, etc., each provided with a conventional track circuit having a track battery TB and a normally energized track relay 1TR, 2RTR, etc., the contacts of which are included in various circuits to govern the operation of the switches and signals in accordance with traffic conditions.

To set up the left to right direction for traffic movements through the single track block, the traffic relays 2RFS and 4LFS are operated to close their right hand contacts to complete a circuit for the signal relay 2RHD, which jointly with relay 2RHS governs local circuits for clearing signal 2RA or 2RB, shown in Fig. 2A of the Young patent and herein in simplified form in Fig. 1A.

The circuit for relay 2RHD as shown may be traced from its winding over the right-hand contacts of the traffic relay 2RFS and front contacts of the track relay 2RTR to wires 28 and 29, and thence in Fig. 1B over front contacts of an indication relay 5NWP controlled by the track relay 5TR, front contacts of the track relay 4LTR, the right-hand contacts of the traffic relay 4LFS and pole-changer contacts of a repeating relay 4RAPC for signal 4RA, and thence directly to terminal C, and to terminal B over front contacts of a normally energized approach locking relay 4LAS and of the track relay 3TR. Relay 4LAS is energized only when the signals 4LA and 4LB are at stop, and relay 4RAPC is energized only when the signal 4RA indicates proceed. Relays 4LAS and 4RAPC are controlled as described in the above-mentioned Young patent, over circuits shown in Fig. 2C of the patent.

The signal 4RB, which controls train movements at slow speed only into the side track, is governed by the signal control relay 4RHS and the track relay 3TR as shown by the local signal circuits in Fig. 1B, while the signal relay 4RHD energized over the line wires 42 and 43. As shown by placing Fig. 1A at the right of Fig. 1B, the circuit for relay 4RHD extends from its winding over front contacts of the track relay 4RTR, line wires 42 and 43, front contacts of the track relay 2LTR, the pole-changer contacts of a repeating relay 2RAPC for signal 2RA and thence to terminal C, and to terminal B at a front contact

of the track relay 1TR over front contact *e* of a normally energized approach locking relay 2LAS.

Relays 2LAS and 2RAPC are controlled over circuits shown in Fig. 2A of the Young patent in such manner that relay 2LAS is energized only when signals 2LA and 2LB are at stop and relay 2RAPC is energized only when signal 2RA indicates caution or proceed.

When switch 1W and its control relay 1WS are reversed, a reverse switch indication relay 1RWS is energized and a front contact of relay 1RWS bridges the contacts of relays 2LAS and 1TR in the circuit for relay 4RHD. It follows that the control limits for signal 4RA extend to the opposing signal 2LA when switch 1W is normal; and only to signal 2RA when switch 1W is reversed.

Considering the right to left direction, it will be seen that the signals 4LA and 4LB are arranged to be controlled by the signal relay 4LHD and signal control relay 4LHS over local circuits shown in Fig. 2C of the Young patent and herein in simplified form in Fig. 1B. The circuit for relay 4LHD is completed over line wires 28 and 29 when the contacts of the traffic relays 4LFS and 2RFS occupy their left-hand position, and includes front contacts of relays 4LTR, 5NWP, 2RTR, 2RAS and 1TR, and pole-changer contacts of relay 2LAPC.

Relay 2RAS is an approach locking relay which is energized only when signals 2RA and 2RB are at stop, and relay 2LAPC is a repeating relay for signal 2LA which is energized only when signal 2LA indicates proceed, the circuits for these relays being shown in Fig. 2A of the Young patent. The slow speed signal 2LB is controlled over the local circuits of Fig. 1A by relays 2LHS and 1TR, and signal 2LA in addition by the signal relay 2LHD which is normally energized over the circuit which includes its winding, front contacts of relay 2LTR, the line wires 40 and 41, front contacts of relay 4RTR, the pole-changer contacts of relay 4LAPC, and front contacts of relays 4RAS and 3TR bridged by a normally open front contact of the reverse switch indication relay 3RWP.

Relay 4RAS is an approach locking relay which is energized only when signals 4RA and 4RB are at stop, and relay 4LAPC is a repeating relay which is energized only when signal 4LA indicates caution or proceed, the circuits for these relays being shown in Fig. 2C of the Young patent.

The apparatus added to the system of the Young patent in accordance with my invention comprises three relays at each station and as shown in Fig. 1A, these comprise an emergency relay 1ER and a pair of emergency signal control relays 2RPS and 2LPS controllable by locally operable levers or preferably by push buttons 2LPB and 2RPB as shown. Relay 1ER is controlled over a back contact *d* of a station disconnect relay 1RPP provided in the communication system, which corresponds to the similarly designated relay shown and described in Letters Patent of the United States No. 2,376,569, issued May 22, 1945, to George W. Baughman. Relay 1RPP is normally held energized by a repeating relay 1RP of the line relay 1R and is provided with a condenser snubbing circuit by which relay 1RPP is retained normally in its energized position as shown, unless relay 1R remains in its released position for a period which is greater than any interval occurring in the normal operation of the

system, such as 5 seconds for example. Relay 1RPP releases automatically, and thereby energizes relay 1ER following an interruption of the communication line circuit due to a fault, and 5 may also be released by the central office operator by opening the disconnect switch DB shown in Fig. 1A. Relay 1RPP, upon releasing, opens the circuit by which relay 1RP is energized by relay 1R, and consequently relays 1RP and 1RPP remain released, and relay 1ER remains energized. After the communication system has been restored to operation, the central office operator is able to reenergize relays 1RP and 1RPP and thereby release relay 1ER by the transmission of 15 a control code to the corresponding station, in the manner described in the Jackel patent, No. 2,411,375, the lower winding of relay 1RP being energized in parallel with the station delivery relay 1D by which, as shown in the Jackel patent 20 above referred to, the control relays 1WS, 2RFS, etc. are selected for operation. Relay 1RP then energizes the slow release relay 1RPP which by closing its front contact *b* prepares a circuit for the upper winding of relay 1RP extending to terminal *B* at the left-hand contact of the line relay 1R, over which relay 1RP is steadily or intermittently energized by relay 1R so as to maintain relay 1RPP picked up until the line circuit is again opened for an abnormally long period. 25 Relays 1RP and 1RPP may also be reenergized in this manner by the transmission of a special "recall" code without operating any of the control relays, as described in the Jackel patent and also in Letters Patent of the United States No. 3,296,812, issued March 19, 1946 to George W. Baughman.

The operator may thus energize the emergency relays 1ER and 3ER for a particular block, in the event of a fault, to isolate that portion of the system while maintaining the remainder in operation by first operating switch DB to release all of the relays RPP and then transmitting codes to reenergize all of these relays except those at the stations to be isolated, as explained in Patent No. 2,376,569 above referred to.

Under normal conditions, the emergency relays 1ER and 3ER occupy their released position in which their contacts connect the windings of the control relays 2RFS, 2LHS, 2RHS, 4LFS, 4LHS and 4RHS to the terminals of the station coding unit provided for the code control of these relays, and these relays therefore function normally as described in the Jackel patent.

The operation of the apparatus of my invention will now be described under different assumed conditions starting first with the left to right traffic direction set up and assuming that the emergency relays 1ER and 3ER become energized when the signaling system is in its normal inactive condition, as shown, with all signals at stop.

When relay 1ER picks up, its contacts *b* and *c* disconnect the traffic relay 2RFS from the coding unit terminals 10 and 32, and relay 2RFS is energized in a direction to close its left-hand contacts over the circuit from terminal *B* at contact *b* of the approach locking relay 2RAS for signals 2RA and 2RB over back contact *c* of relay 2RPS, front contact *c* of relay 1ER through relay 2RFS and over contacts *b* of relays 1ER and 2RPS to terminal *C* at contact *g* of relay 2RAS. The operation of contacts *d*, *e* and *f* of relay 1ER disconnects relays 2RHS and 2LHS from the coding unit terminals 13, 15 and 31 and connects their

upper windings, in series, to contacts of relays 2RPS and 2LPS.

Relay 2RFS therefore operates its contacts to the left to disconnect relay 2RHD from the line wires 28 and 29 and to connect these wires to terminals B and C as required for traffic movement from right to left.

Similar operations occur in response to the energization of relay 3ER in Fig. 1B, except that relay 4LFS is energized in a direction to close its right-hand contacts, but under the assumed condition these contacts are already in that position.

If it should happen that relay 1ER becomes energized when signal 2RA or 2RB has been cleared for an approaching train, relay 2RAS will be released and the operation of relay 2RFS will be delayed until the signal is restored to stop by the train, and relay 2RAS is reenergized. A similar delay occurs in the operation of relay 4LFS under corresponding conditions.

From the foregoing it will be seen that in the event a failure of the communication line circuit occurs, the emergency relays 1ER and 3ER pick up at the opposite ends of each single track block, each traffic relay such as relay 4LFS at the existing exit end of a block being retained in its exit end position so that it continues to supply energy to the line circuit system at that end, while each traffic relay such as relay 2RFS at an existing entering end of a block is operated to its exit end position so that it also supplies energy to the line circuit system; in other words, both ends of the block are conditioned to be exit ends. The signal relays are disconnected from the line circuit at both ends, but the apparatus is in condition to be set up for either direction of operation by local "entrance end" control, irrespective of the direction previously established.

It will now be assumed that relays 1ER and 3ER are energized and that a train moving from left to right arrives at the station of Fig. 1A. To clear signal 2RA for this train, the push button 2RPB is operated by the train crew or local operator completing a circuit from terminal B at contact *a* of relay 1ER over contact *g* of relay 1TR, the normally closed "pull" contact *c* of button 2RPB, contact *b* of button 2LPB, contact *a* of button 2RPS through relay 2RPS to terminal C. Relays 2RPS picks up, completing a stick circuit at its contact *a* over which it is held energized after button 2RPB is released, until relay 1TR or 1ER is released, or until the operation of relay 2RPS is cancelled manually by opening contact *c* of button 2RPB or contact *b* of button 2LPB. When relay 2RPS picks up, its contacts *b* and *c* reverse the polarity of the current supplied to the traffic relay 2RFS, which relay thereupon operates its contacts to the right or entrance end position, causing relay 2RHD to pick up provided the block is vacant. A circuit is also closed by relay 2RPS from terminal B at contact *a* of relay 1ER over contact *g* of relay 1TR, contact *c* of button 2RPB, contact *b* of button 2LPB, front contacts *e* of relays 2RPS and 1ER through relay 2RHS in the reverse direction and through relay 2LHS in the normal direction, and thence over front contacts *d* of relays 1ER and 2RPS to terminal C. Relay 2RHS operates to close its right-hand contacts while relay 2LHS being oppositely energized maintains its contacts in the normal left-hand position as shown.

Assuming the signal relay 2RHD to be energized, a circuit for clearing signal 2RA is now closed from terminal B at contact *c* of relay 2LAS

over the normal contact *a* of relay 2LHS, contact *d* of relay 1TR, the reverse contact *a* of relay 2RHS, contact *b* of relay 2RHD and contact *c* of relay 1NWP through the mechanism of signal 2RA to terminal C causing signal 2RA to indicate caution or proceed and releasing the approach locking relay 2RAS in the usual manner, as explained in the Young patent.

When the train governed by signal 2RA enters section 1T, relay 1TR releases. Relay 2RPS is released by the opening of contact *g* of relay 1TR, and relay 2RHS is restored to normal by the closing of the circuit from terminal B through the lower windings of relays 2RHS and 2LHS in series to terminal C at back contact *f* of relay 1TR. Signal 2RA returns to the stop position, and relay 2RAS is reenergized in the usual manner, completing a circuit at its front contacts *h* and *g* to energize the traffic relay 2RFS in a direction to close its left-hand contacts, which relay therefore reverts to its exit end position in which it connects terminals B and C to the line wires 28 and 29 in place of relay 2RHD.

Assuming next that signal 2RA had been cleared by remote control and stood at clear when relay 1ER became energized due to an interruption of the communication line circuit, relay 2RAS will be in its released position with its contacts *g* and *h* open, and relays 2RFS and 2RHS, which are of the magnetic stick type, will remain de-energized with their contacts in the right-hand position following the energization of relay 1ER. Relay 2RFS therefore will maintain relay 2RHD energized and relays 2RHD and 2RHS will maintain signal 2RA at clear until the train governed thereby enters section 1T, whereupon relays 2RFS and 2RHS will be operated to close their left-hand contacts in response to the release of relay 1TR as already described. It will be seen therefore that the energization of the emergency relays cannot cause any signal which has been cleared to be put to stop in front of an approaching train.

It will now be assumed that signal 2LA is to be cleared locally in place of signal 2RA when relays 1ER and 3ER are energized. In this case the push button 2LPB is operated to complete a circuit at its contact *a* for relay 2LPS similar to that for relay 2RPS already traced. Relay 2LPS picks up and completes a circuit over its contacts *b* and *c* through relay 2LHS in the reverse direction and through relay 2RHS in the normal direction, so that in this case relay 2LHS operates to close its right-hand contacts and relay 2RHS maintains its contacts in the normal position as shown. If the signal relay 2LHD is energized, the closing of the right-hand contact *a* of relay 2LHS completes a circuit for energizing signal 2LA corresponding to that for signal 2RA already traced.

It will now be assumed that signal 2RB or 2LB is to be cleared. In this case the train crew will reverse switch 1W by the operation of its hand throw lever before push button 2RPB or 2LPB is operated, and to unlock the hand throw lever, will first operate a selector lever by which the dual selector contacts DS are opened, the selector lever being restored to normal to close these contacts after the switch is locked in its reverse position. Under centralized operation the closing of the contacts DS with the switch reversed and relay 1WS in its normal position would cause power to be supplied to the switch machine over the normal contact *a* of relay 1WS to restore the switch to normal, but this circuit is now open

at back contact *h* of relay 1ER. Furthermore, under normal conditions neither relay 1NWP nor 1RWP can be energized to complete a signal circuit unless the switch and its control relay occupy corresponding positions, but under the emergency condition, contact *b* of relay 1WS in the circuit for relays 1NWP and 1RWP is bridged by contact *f* of relay 2RPS or by contact *d* of relay 2LPS. When one of these relays becomes energized, allowing relay 1RWP to become energized over the switch circuit controller contact *R* and by closing its contact *c* or *d* to complete the circuit for clearing signal 2RB or 2LB.

Upon the arrival of the train governed by signal 2RA or 2RB at Station No. 3, switch 3W may be similarly operated to normal or reverse by means of its hand throw lever. Relay 4RPS may then be picked up by the operation of the push button 4RPB, whereupon relay 4RPS completes a circuit at its contacts *b* and *c* over back contacts *d* and *e* of relay 4LPS and front contacts *d* and *e* of relay 3ER to operate relay 4RHS to reverse and relay 4LHS to normal. The closing of contact *d* of relay 4RPS permits relay 3NWP or 3RWP to become energized irrespective of the position of relay 3WS, allowing signal 4RA or 4RB to be cleared, the clearing of signal 4RA being dependent upon the energization of relay 4RHD as will be clear from the drawing.

The operations for clearing signal 4LA or 4LB for a traffic movement in the opposite direction is similar to operations already described, and a detailed description thereof is deemed unnecessary.

It is to be understood that the main track block having the entering signals 4RA and 2LA may also be provided with a system of reversible signal circuits which may be controlled by two additional traffic relays similar to relays 2RFS and 4LFS, as shown for example, in Letters Patent of the United States No. 2,404,303 issued July 16, 1946, to John C. Law. It will be clear that my invention may be applied to this system by the provision of additional contacts on relays 1ER, 3ER, 2LPS and 4RPS for the control of the additional traffic relay at each station.

The local control equipment at each station is so arranged that after a signal has been cleared as above described it can be restored to stop if desired, and for that purpose the push buttons employed are circuit controllers of the three-position type having two contacts *a* and *b* operable by pressing the button, and two "pull" contacts *c* and *d* operable by a movement of the button in the opposite direction, such for example as shown in Figs. 5 to 7 of Letters Patent of the United States No. 2,244,326, issued June 3, 1941, to Herbert L. Bone et al.

As explained above, when signal 2RA is to be cleared locally, button 2RPB is pressed to pick up relay 2RPS, which reverses relays 2RFS and 2RHS and if traffic conditions are proper, signal 2RA will clear and relay 2RAS will release.

If for any reason the signal fails to clear or if there is a change in plans after the signal has been cleared, the set-up can be cancelled and the equipment restored to its original condition by pulling the knob of button 2RPB to open its contact *c* in the stick circuit for relay 2RPS to cause the release of that relay, and to close contact *d* of button 2RPB to connect terminal C to the local restoring circuit for relays 2RHS and 2LHS to restore the operated signal control relay to normal. The release of relay 2RPS reconnects relay 2RFS to contacts *g* and *h* of relay 2RAS, so

that relay 2RFS is operated to its exit end position as soon as relay 2RAS becomes energized following the return of the signal to its stop position as the result of the operation of relay 2RHS to normal.

The systems of the Young and Law patents hereinbefore referred to include provisions for the central office control of electric switch locks for governing the operation of outlying hand throw switches such as the switch 5W, Fig. 1B, by which a train is enabled to enter a block at an intermediate point. These arrangements comprise means whereby the train crew is enabled to unlock the switch by current received at the switch location over the signal circuits from both directions, following the release by the train crew of a locally controlled relay 5NWP when the central office operator has positioned the traffic relays so as to supply current to the signal circuits at both ends of the block. Since the conditions required for switch lock release are identical with those established by the operation of the emergency relays 1ER and 3ER, it will be clear that no special provisions of any kind are needed in order to provide for the control of electric switch locks when applying my invention to centralized traffic control systems of the types referred to.

Although I have herein shown and described only one form of apparatus embodying my invention, it will be understood that various changes and modifications may be made therein within the scope of the appended claims without departing from the spirit and scope of my invention.

Having thus described my invention, what I claim is:

1. In a centralized traffic control system for governing traffic movements in either direction over a stretch of a single track railroad having an entering signal at each end controllable by a signal relay in accordance with traffic conditions and also subject to manual control by the operation of a signal control relay, traffic relays at the ends of the stretch operable to corresponding positions in which they serve to connect the signal relay at either end of the stretch to a system of reversible signal circuits reflecting traffic conditions therein and to energy thereto at the opposite end of the stretch; a communication system employing a normally energized line circuit connecting the signal locations with a control office for effecting the remote control of said traffic relays and said signal control relays, normally disabled local manual control means for each signal control relay, an emergency relay at each signal location effective when operated to render the signal control relay at that location responsive to the operation of its local control means, means for operating said emergency relays automatically when said communication line circuit becomes disabled due to a fault, means for operating both traffic relays to positions in which they supply energy to said line circuit system in response to the operation of said emergency relays, and means for enabling either of said traffic relays to be restored to its opposite position in response to the operation of the local control means for the adjacent signal.
2. In a centralized traffic control system for railroads, a stretch of single track having entering signals at each end for governing traffic movements in opposite directions through the stretch, a signal relay and a signal control relay at each end of the stretch, a system of reversible signal circuits reflecting traffic conditions in said stretch and arranged to be supplied

11

with energy at either end to effect the energization of the signal relay at the opposite end of the stretch, circuits for clearing each signal controlled by the adjacent signal relay subject to manual control by the operation of the adjacent signal control relay, a communication system employing a normally energized line circuit extending from a control office to said signal locations for manually governing said signal control relays and for controlling the direction of energization of said system of reversible signal circuits, an emergency relay and normally disabled local control means governed thereby at each end of the stretch, means selectively responsive to a prolonged interruption of said communication line circuit for operating the emergency relays at both ends of the stretch, means controlled by said emergency relays when operated for supplying energy to said system of reversible signal circuits at both ends of the stretch, and means controlled by each operated emergency relay for enabling the associated local control means to govern the operation of the adjacent control relay and to control said signal circuit system to render the adjacent signal relay responsive to the energy supplied thereto at the opposite end of the stretch.

3. In a centralized traffic control system for railroads, a stretch of single track having entering signals at each end for governing traffic movements in opposite directions through the stretch, a reversible circuit system reflecting traffic conditions in said stretch and effective when supplied with energy at either end of the stretch to govern the clearing of the signal at the opposite end of the stretch, a communication system having a station at each end of the stretch connected by a line circuit with a control office, traffic relays normally controllable from said office over said line circuit to supply energy to said reversible circuit system at one end or the other according to the desired direction of traffic movement, an emergency relay at each station reflecting the condition of said communication line circuit and arranged to assume its operated position when said circuit is disabled due to a fault, means controlled by each emergency relay when operated for supplying energy to said reversible circuit system at the adjacent end of the stretch, and local signal control means at each station rendered effective by the operation of the emergency relay at that station to discontinue the energy supplied thereby to said reversible circuit system to render the adjacent signal responsive to energy supplied by the operation of the emergency relay at the opposite end of the stretch.

4. In a centralized traffic control system for railroads, a stretch of single track having entering signals at each end for governing traffic movements in opposite directions through the stretch, a traffic relay at each end of the stretch operable between entrance and exit end positions, a communication system having a station at each end of the stretch connected by a line circuit with a control office and providing means normally available for operating either traffic relay to its entrance end position and the other traffic relay to its exit end position, circuits controlled in accordance with traffic conditions in said stretch for clearing either signal for a traffic movement through the stretch in a direction determined by the positions of said traffic relays, an emergency relay at each station, means responsive to a fault which disables said line circuit for operating said emergency relays, means

12

controlled by each emergency relay when operated for operating the adjacent traffic relay to its exit end position, and local signal control means at each station rendered effective by the operation of the emergency relay at that station for restoring the adjacent traffic relay to its entrance end position whereby either direction of traffic movement may be established by local control from the corresponding entrance end of the stretch.

5. In a system of centralized traffic control for a stretch of railroad track having a signaling system comprising a system of reversible circuits extending the length of said stretch governed by traffic conditions in said stretch and by traffic relays at the ends of the stretch, each traffic relay having contacts which in a first position connect a source of energy to said system of reversible circuits and in a second position connect a signal relay thereto, a signal at each end of the stretch for governing traffic movements into said stretch controlled jointly by the adjacent signal relay and by a signal control relay, a code communication system employing a normally energized line circuit which extends from a control office to stations at the end of said stretch, for the control of said traffic and signal control relays from said office, the combination with the foregoing apparatus of an emergency relay at each station having contacts which are moved from a normal to an operated position in response to the prolonged deenergization of said line circuit, circuit means at each station effective only when the contacts of the associated emergency relay are in their operated position to disconnect the adjacent signal from said system of reversible circuits and to connect a source of energy thereto at the adjacent end, and manually operable means for locally controlling the circuit means at each station to cause said source of energy to be disconnected from said system of reversible circuits and the adjacent signal relay to be connected thereto.

6. In a system of centralized traffic control for a stretch of railroad track having a signaling system comprising a system of reversible circuits extending the length of said stretch governed by traffic conditions in said stretch and by traffic relays at the ends of the stretch, each traffic relay having contacts which in a first position connect a source of energy to said system of reversible circuits and in a second position connect a signal relay thereto, a signal at each end of the stretch for governing traffic movements into the stretch, a signal control relay at each end of the stretch having contacts effective in a first position to hold the adjacent signal at stop and in a second position to render such signal responsive to the energization of the adjacent signal relay, a code communication system employing a normally energized line circuit which extends from a control office to stations at the ends of the stretch, for the control of said traffic and signal control relays from said office, the combination with the foregoing apparatus of an emergency relay at each station having contacts which are moved from a first to a second position in response to the prolonged deenergization of said line circuit, circuit means at each station effective if the contacts of the emergency relay at such station are moved to their second position when the adjacent signal is at stop for causing the adjacent signal relay to be disconnected from said system of reversible circuits and a source of energy to be connected thereto at the

13

adjacent end, and manually operable means for locally controlling the circuit means at each station to cause said source of energy to become disconnected from said system of reversible circuits and the adjacent signal relay to be connected thereto.

7. In a system of centralized traffic control for a stretch of railroad track having a signaling system comprising a system of reversible circuits extending the length of said stretch governed by traffic conditions in said stretch and by traffic relays at the ends of the stretch, each traffic relay having contacts which in a first position connect a source of energy to said system of reversible circuits and in a second position connect a signal relay thereto, a signal at each end of the stretch for governing traffic movements into the stretch, a signal control relay at each end of the stretch having contacts effective in a first position to hold the adjacent signal at stop and in a second position to render such signal responsive to the energization of the adjacent signal relay, a code communication system employing a normally energized line circuit which extends from a control office to stations at the ends of the stretch for the control of said traffic and signal control relays from said office, the combination with the foregoing apparatus of an emergency relay at each station having contacts which are moved from a first to a second position in response to the prolonged deenergization of said line circuit, circuit means for operating each traffic relay and the associated signal control relay in accordance with code controls transmitted from said office to the adjacent station of said communication system effective only when the contacts of the adjacent emergency relay are in their first position, circuit means effective when the contacts of said emergency relay are in their second position and the adjacent signal is at stop for operating the contacts of said traffic relay from their second to their first position, and manually controllable means effective only when the contacts of said emergency relay are in their second position for operating the contacts of the associated traffic relay to their second position and for also operating the contacts of the associated signal control relay to their second position.

8. In a system of centralized traffic control for a stretch of railroad track having a signaling system comprising a system of reversible circuits extending the length of said stretch governed by traffic conditions in said stretch and by traffic relays at the ends of the stretch, each traffic relay having contacts which in a first position connect a source of energy to said system of reversible circuits and in a second position connect a signal relay thereto, a signal at each end of the stretch for governing traffic movements into the stretch, a signal control relay at each end of the stretch having contacts effective in a first position to hold the adjacent signal at stop and in a second position to render such signal responsive to the energization of the adjacent signal relay, a code communication system employing a normally energized line circuit which extends from a control office to stations at the ends of the stretch for the control of said traffic and signal control relays from said office, the combination with the foregoing apparatus of an emergency relay at each station having contacts which are moved from a first to a second position in response to the prolonged deenergization of said line circuit, circuit means for operating each

14

traffic relay and the associated signal control relay in accordance with the controls transmitted from said office to the adjacent station of said communication system effective only when the contacts of the adjacent emergency relay are in their first position, circuit means effective when the contacts of said emergency relay are in their second position and the adjacent signal is at stop for operating the contacts of said traffic relay from their second to their first position, manually controllable means effective only when the contacts of said emergency relay are in their second position for operating the contacts of the associated traffic and signal control relays to their second positions, and means at each end of the stretch effective when a train enters the stretch at that end with the contacts of the adjacent emergency relay in their second position for operating the contacts of the associated traffic and signal control relays to their first position.

9. In a system of centralized traffic control for a stretch of railroad track having a signaling system comprising a system of reversible circuits extending the length of said stretch governed by traffic conditions in said stretch and by traffic relays at the ends of the stretch, each traffic relay having contacts which in a first position connect a source of energy to said system of reversible circuits and in a second position connect a signal relay thereto, a signal at each end of the stretch for governing traffic movements into the stretch, a signal control relay at each end of the stretch having contacts effective in a first position to hold the adjacent signal at stop and in a second position to render such signal responsive to the energization of the adjacent signal relay, a code communication system employing a normally energized line circuit which extends from a control office to stations at the ends of the stretch for the control of said traffic and signal control relays from said office, the combination with the foregoing apparatus of an emergency relay at each station having contacts which are moved from a first to a second position in response to the prolonged deenergization of said line circuit, a local control relay at each station, manually operable means effective only when the contacts of the adjacent emergency relay are in their second position for operating said control relay from a first to a second position, circuit means for operating each traffic relay and the associated signal control relay in accordance with the controls transmitted from said office to the adjacent station of said communication system effective only when the contacts of the adjacent emergency relay are in their first position, circuit means controlled by each local control relay for operating the adjacent traffic relay and signal control relay effective only when the contacts of the adjacent emergency relay are in their second position.

10. In a system of centralized traffic control for a stretch of railroad track having a signaling system comprising a system of reversible circuits extending the length of said stretch governed by traffic conditions in said stretch and by traffic relays at the ends of the stretch, each traffic relay having contacts which in a first position connect a source of energy to said system of reversible circuits and in a second position connect a signal relay thereto, a signal at each end of the stretch for governing traffic movements into said stretch controlled jointly by the adjacent signal relay and by a signal control relay, a code communication system employing

15

a normally energized line circuit which extends from a control office to stations at the end of said stretch for the control of said traffic and signal control relays from said office, the combination with the foregoing apparatus of an emergency relay at each station having contacts which are moved from a normal to an operated position in response to the prolonged deenergization of said line circuit, a local control relay at each station, a manually operable circuit controller for actuating each local control relay rendered effective when the contacts of the adjacent emergency relay are in their operated position, circuit means at each station rendered effective when the contacts of the adjacent emergency relay are in their operated position to connect a source of energy or said signal relay to said reversible system of circuits in accordance with the position of said local control relay, and means for restoring each local control relay to its normal position rendered effective when a train enters the stretch at the adjacent end.

11. In a system of centralized traffic control for a stretch of railroad track having a signaling system comprising a system of reversible circuits extending the length of said stretch governed by traffic conditions in said stretch and by traffic relays at the ends of the stretch, each traffic relay having contacts which in a first position connect a source of energy to said system of reversible circuits and in a second position connect a signal relay thereto, a signal at each end of the stretch for governing traffic movements into said stretch controlled jointly by the adjacent signal relay and by a signal control relay, a code

10

15

20

25

35

16

communication system employing a normally energized line circuit which extends from a control office to stations at the end of said stretch for the control of said traffic and signal control relays from said office, the combination with the foregoing apparatus of an emergency relay at each station having contacts which are moved from a normal to an operated position in response to the prolonged deenergization of said line circuit, circuit means at each station effective only when the contacts of the associated emergency relay are in their operated position to disconnect the adjacent signal relay from said system of reversible circuits and to connect a source of energy thereto at the adjacent end, and manually controllable means at each station effective only when the associated emergency relay is in its operated position for controlling the circuit means at such station to disconnect said source of energy from said system of reversible circuits and to connect the adjacent signal relay thereto.

Certificate of Correction

Patent No. 2,520,838

August 29, 1950

THOMAS W. HAYS

It is hereby certified that error appears in the printed specification of the above numbered patent requiring correction as follows:

Column 12, line 36, after the word "signal" insert *relay*;
and that the said Letters Patent should be read as corrected above, so that the same may conform to the record of the case in the Patent Office.

Signed and sealed this 21st day of November, A. D. 1950.
